MECHANICAL TOY

Filed Dec. 8, 1928

UNITED STATES PATENT OFFICE

FRANK B. RENTZ AND WILLARD E. FANTLE, OF YANKTON, SOUTH DAKOTA

MECHANICAL TOY

Application filed December 8, 1928. Serial No. 324,635.

Our invention relates to a mechanical toy and has for its object to provide such a toy that is actuated by a projectile arranged to be propelled up an elevating race and precipitated onto a motion transmitting power device for operating the same.

To the above ends, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the toy;

Fig. 2 is a view partly in elevation and partly in section taken on the line 2—2 of Fig. 1;

Fig. 3 is a fragmentary detail view principally in section taken on the line 3—3 of Fig. 1;

Fig. 4 is a fragmentary detail view principally in section taken on the line 4—4 of Fig. 1;

Fig. 5 is a fragmentary detail view in section taken on the line 5—5 of Fig. 1; and

Fig. 6 is a view principally in section taken on the line 6—6 of Fig. 2.

The numeral 7 indicates a rectangular sheet metal base having an upstanding marginal flange 8. Mounted on the base 7 is a race that is channel shape in cross section and includes an elevating section 9 and a return section comprising an upper member 10 and a lower member 11 with a vertical gap 12 therebetween. The elevating section 9 and the return member 10 of said race are detachably supported in part from the base 7 by a plurality of braces 13, as shown three. These braces 13 are detachably secured to the base 7 and race by having on their ends laterally extended tongues 14 that are removably held in loops 15 on said base and bottom of the race.

Longitudinally aligned with the lower or receiving end of the elevating section 9 of the race is a catapult comprising a horizontal plunger 16 which works through the front member of the flange 8 and is provided with a propelling spring 17. This spring 17 en-

circles the inner end portion of the plunger 16 and is compressed between the flange 8 and a head 18 on the inner end of said plunger. The outer end portion of the plunger 16 works through a bracket 19 on the flange 8 that holds the same for straight line movement. A knob or finger piece 20 is applied to the extreme outer end of the plunger 16 by which said plunger may be held and operated to retract the same and compress the spring 17 and propel said plunger when the knob 20 is released. An open ended rectangular casing 21 is provided for the spring 17 and respective end portion of the plunger 16. This casing 21 extends longitudinally between the front end of the flange 8 and the lower end of the elevating section 9 of the race. The outer end of the casing 21 is closed by the front end of the flange 8 and its inner end is rigidly secured to the elevating section 9 of the race. The casing 21 is held in position at the right hand member of the flange 8 by an angle 22 secured to the base 7 and engages the left hand side and top of said casing, see Fig. 1.

By thus securing the casing 21 to the base 7 it in turn holds the adjacent end of the elevating section 9 of the race in place. An endwise move of the casing 21 away from the front member of the flange 8 will carry the connected portion of the race with it and release said casing from the angle 22. A power wheel 23 fixed to a horizontal shaft 24 journaled in bearings 25 on the base 7 is arranged to rotate in the gap 12. The bearings 25 are provided at their lower ends with outturned feet 26 that are detachably secured to the base 7 by loops 27 through which they extend. By springing the bearings 25 toward each other they may be detached from the loops 27. The rim 28 of the wheel 23 is in the form of a channel that is segmental in cross section. A plurality of circumferentially spaced pockets 29 are formed on the periphery of the wheel 23 by cutting and pressing outwardly extended radial lugs 30 from the bottom of the channeled rim 28. The wheel 23 is rotated by one or more projectiles 31 in the form of balls, as shown two. Formed in the bottom of the race at the

junction of the delivery end of the return race section 11 and in front of the plunger head 18 is a projectile positioning seat 32 in the form of a depression into which the projectiles 31 roll from the return member 11 of the race. On the left side of the casing 21 is a forwardly projecting stop plate 33 which prevents the projectiles 31 from rolling out of the seat 32 as they are delivered thereto from the return section 11 of the race.

To impart rotary movement to the wheel 23 by the use of one or more of the projectiles 31, the catapult is repeatedly operated by drawing its plunger 16 outward to compress the propelling spring 17 and then release said plunger for action on the projectile 31 on the seat 32 and drive the same up the elevating section 9 of the race. The seat 32 is so arranged that when a projectile 31 is resting thereon the same engages the plunger head 18 and is held thereby slightly raised on the front edge portion of said seat so that when the plunger 16 is retracted the projectile will roll into the seat 32 and follow the plunger 16 to be engaged by the head 18 thereof when said plunger is released. A blow on the projectile 31 by the plunger 16 will drive the same up the elevating section 9 of the race.

A stop 33 on the plunger 16 is arranged to engage the front face of the flange 8 and limit the projecting movement of said plunger by its propelling spring 17. The force of a blow delivered by the catapult of course depends on the amount of tension placed on the propelling spring 17 by the retraction of the plunger 16 and this blow must have sufficient force to drive the projectile 31 over the upper end of the elevating section 9 of the race and onto the return member 10 thereof.

To prevent a projectile 31 from leaving the race as the same reaches the top of the elevating section 9, a cover guard 34 is attached to the return member 10 of the race. A projectile 31 delivered to the return race member 10 from the elevating section 9 is precipitated from the lower end thereof and directed into one of the pockets 29 at one side of the dead center of the wheel 23 by a short depending spout section 35 on said member 10. As a projectile 31 is delivered into one of the pockets 29 the weight thereof will overcome the inertia of the wheel 23 and impart the initial rotary movement thereto. As the projectiles 31 are successively deposited in the pockets 29 under the action of the catapult a continuous rotary movement is imparted to the wheel 23. The speed at which the wheel 23 is rotated of course depends on how fast the catapult is operated.

A projectile 31 will remain on the wheel 23 until the lug 30 of the respective pocket 29 reaches a downwardly inclined position in which the projectile 31 will roll therefrom

and be precipitated onto the receiving end of the return member 11 of the race. The receiving end of the return member 11 of the race is provided with an upstanding guard 36, that is channel shape in cross section, with its side flanges loosely embracing the active side of the wheel 23. This guard 36 prevents a projectile 31 from leaving its pocket 29 before the lug 30 of said pocket has moved away from the transverse portion of said guard a distance sufficient to permit the projectile 31 to pass between said transverse portion of the guard 36 and the outer end of said lug and direct the projectile 31 onto the receiving end of the return member 11.

A projectile 31 discharged from the wheel 23 onto the return member 11 of the race will roll down said race and onto the seat 32 and be automatically positioned in respect to the catapult. Or if there is a projectile 31 on the seat 32 the second projectile will engage the same and be held thereby. When the projectile 31 on the seat 32 is driven therefrom by the catapult, the second projectile will roll onto said seat and be automatically positioned for the next operation of the catapult.

The return member 11 of the race is detachably secured to the base 7 at its rear end by a short brace, not shown, and its front end is detachably secured to the race section 9 and casing 21 by being sprung between the adjacent side flange of said section and said casing and frictionally held thereby. This short brace is attached to the base 7 in the same manner as the braces 13.

On the left hand end of the shaft 24 is a crank 38 for operating an inanimate figure 39. This figure 39, as shown, is in the form of a man cut from relatively stiff material such as sheet metal. Said figure 39 is supported at one side of the crank 38 for rocking movement by having one of its feet pivoted at 40 to the base 7 and the arms 41 of said figure are pivoted to the body thereof and to said crank. Obviously, under the rotation of the crank 38 by the wheel 23 movement is imparted to the figure 39 which gives the same the appearance of operating the crank 38.

At the opposite side of the wheel 23 from the figure 39 is a well 42 for holding a body of water X. This well 42 is detachably secured to the base 7 by a tongue 43 which extends through a loop 44 on said base and has friction interlocking contact therewith, as indicated at 45. At the front and top of the well 42 is an inclined discharge spout 46 and below said spout is a return spout 47. The inner end of the spout 46 affords a trip 48. On the sides of the well 25 are X-shaped supports 49 connected by a cross-tie rod 50 which gives the well 42 the appearance of the old oaken bucket type. The shaft 24 extends directly under and parallel to the

rod 50 and has formed thereon a crank 51. A bucket 52 is pivotally suspended by a bail 53 from the crank 51 for raising and lowering movements into and out of the well 42. The bottom of the bucket 52 is round for a purpose that will presently appear. Under the rotation of the shaft 24 the bucket 52 is submerged in the body of water X to fill the same then raised to a point above the well 42 and thereafter lowered into the well 42 by the crank 51.

During the horizontal or upper and lower movements of the crank 51 the bucket 52 is moved thereby in the arcs of circles and during this movement of the bucket, as the same is lowered into the well 42, its round bottom strikes the trip 48 and tips the bucket 52 into a position, as shown by broken lines in Fig. 6 and causes said bucket to spill its contents onto the spout 46. From the spout 46 the water spilled from the bucket 52 flows onto the spout 47 and is returned thereby to the well. It will thus be seen that once during each rotation of the wheel 23 a bucket of water is raised from the well 42 and spilled onto the spout 46.

Mounted on the shaft 24 is a small pulley 53 for the application of a belt, not shown, for use in operating a second toy for instance, a wind mill.

From the above description, it is evident that the arrangement of the several movable parts of the toy is such that when operated by the projectile 31 it gives the appearance of a man operating a windlass shaft to draw water from an open well.

What we claim is:

1. A mechanical toy having a catapult, a race having an elevating section leading from the catapult and a return section leading to the catapult and having a gap, a projectile, said catapult being arranged to project the projectile up said elevating section and onto the return section of the race, a wheel mounted to rotate in said gap, said wheel having a plurality of circumferentially spaced pockets, the discharge end of the upper member of the return section of the race being arranged to direct the projectile into one of the pockets in the wheel at one side of a dead center for causing the projectile to impart a rotary movement to the wheel, said race having positioning means for centering the projectile in respect to the catapult, the return section of the race being arranged to deliver the projectile to said positioning means.

2. A mechanical toy having a rotatable member, a well, a bucket, operating connections for raising and lowering the bucket in the well, said well having a discharge spout, a trip, said bucket being arranged to engage the trip during its movement in the well and spill its contents onto the discharge spout, and means for catching the spilled contents

of the bucket and returning the same to the well.

3. A mechanical toy having a rotatable crank-equipped shaft, means for rotating the shaft, a jointed figure of a man operable by the crank of said shaft to give the figure the appearance of operating the crank, a well, and a bucket arranged to be actuated by the shaft to raise and lower the bucket in the well.

In testimony whereof we affix our signatures.
